ELECTRIC SWITCH

Harry C. Swan, Dayton, Ohio, assignor to General Motors Corporation, Detroit, Mich., a corporation of Delaware

Application December 15, 1950, Serial No. 200,976

8 Claims. (Cl. 200—113)

1

This invention relates to an electric switch operative to control two electrical circuits in accordance with the current flow therethrough.

It is among the objects of the present invention to provide a thermoelectric switch having all of the characteristics of the switch disclosed in the patent to Werner, No. 2,242,769, issued May 20, 1941, but differing in construction, resulting in a much smaller switch which permits it to be mounted within the frame of the electric motor it is adapted to control, thereby eliminating the addition of undesirable housing provisions which destroy the symmetry of the motor and ruin its appearance.

Reducing the size of the switch not only substantially reduces its cost of manufacture, but also reduces the amount of materials necessary for the production of a switch of larger proportions, such material reduction being an important factor particularly when material supplies are being curtailed and restricted, especially for commercial use.

Further objects and advantages of the present invention will be apparent from the following description, reference being had to the accompanying drawings wherein a preferred embodiment of the present invention is clearly shown.

In the drawings:

Fig. 1 is a plan view of the switch shown in full contact making position.

Fig. 2 is a view similar to Fig. 1, showing the switch in a position in which one of its circuits is broken and the other maintained.

Fig. 3 is a similar view of the switch showing both of its circuits broken.

Fig. 4 is an end view of the switch.

Fig. 5 is a perspective view of the switch sans the insulating plate which carries the stationary contacts and upon which the switch is mounted.

Fig. 6 is a side view of the switch looking in the direction of arrow 6 of Fig. 4.

The plate 20 upon which the switch is mounted may be of any suitable insulating material and for purposes of illustration, the present switch is shown made of a transparent synthetic insulating compound through which the switch mechanism may be viewed. This insulating base has two stationary contacts 21 and 22 mounted thereupon in any suitable manner and in proper relative positions one to the other. The switch mechanism consists of a rigid frame 23, U-shaped for a portion of its length, which portion consists of the top web portion 24 and two depending side portions 25 and 26 having ears 27 and 28 respectively which extend through the insulating

2

base 20 and are twisted so as to rigidly lock the frame to the base 20. Frame 23 has two angular projections 30 and 31 substantially at right angles to the web portion 24 thereof. The angular projection 30 of the rigid frame 23 has two flexible contact blades 32 and 33 secured thereto with a spring 34 sandwiched therebetween. These superposed elements 32, 34 and 33 are anchored to the projection 30 by means of a rivet 35. Blade spring 32 at its free end, or more particularly the end thereof opposite its anchored end, has a contact element 37 attached thereto which is adapted to cooperate with the stationary contact 21 to make and break a circuit. Likewise, flexible blade 33 has a contact 38 secured at its free end, this contact 38 cooperating with the stationary contact 22 to make and break another electric circuit. The flexible blade spring 34, secured to the rigid base projection 30 between the two flexible contact blades 32 and 33, carries the abutment 40 which extends edgewise into centrally slotted portions in the two contact carrying flexible blades 32 and 33. The Fig. 5 clearly illustrates the slot 41 in the flexible blade 33, this slot 41 being identical to slot 42 in the flexible blade 32 as shown in Fig. 5. The abutment 40 is secured to spring 34 by means of a projection 43 on the abutment which extends through an opening in the spring 34 and is riveted over the spring. It will be noted that the abutment 40 is mounted edgewise upon spring 34 and is substantially at right angles thereto so that said abutment moves transversely or edgewise through the slotted flexible contact carrying blades 32 and 33. The one end of the abutment 40, more particularly the end thereof adjacent to its point of anchor to spring 34, has one end of the thermoelectric element 50 secured thereto so as to be in electrical connection therewith. The other end of this thermoelectric element is secured to an adjustable member 51 insulatingly supported upon the frame projection 31 by an insulating coil 52. Normally the spring 34 urges the abutment 40 in a counterclockwise direction as regards Fig. 1, movement of the abutment 40 by the spring however being opposed by the thermoelectric element 50 which tends to move the abutment in the opposite direction under certain conditions, but under other conditions, will permit movement of the abutment by the spring 34 in a counterclockwise direction as regards Figs. 1, 2 and 3.

The abutment member 40 has two contiguous saw-tooth shaped notches 55 and 56 in its end edge opposite the edge or portion to which the thermoelectric element 50 is attached. This

notch end edge of the abutment 40 moves through the slotted contact carrying flexible blades 32 and 33 in a plane at right angles to the plane surface of said blades. The flexible blade 32 has a resilient finger 60 provided thereon, this finger being shown integral with blade 32 and extending therefrom at a point in close proximity to the contact 37 thereon. The finger 60 is of such a length that when its free end is seated in the saw tooth notch 56 of the abutment member 40, said finger 60 is biased to exert a pushing force upon the contact carrying flexible plate 32. Likewise plate 33 is provided with a resilient finger 61 extending therefrom and secured thereto in the vicinity of the contact 38 thereon, this finger 61 being likewise biased when its free end is seated in the saw tooth notch 55 of the abutment 40, the finger being operative to exert a pushing force upon the flexible contact carrying blade 33. The knife edges of the saw tooth notches 55 and 56 are, as has been said before, contiguous, being spaced a predetermined distance one from the other. When the position of the abutment 40 is as illustrated in Fig. 1, notches 55 and 56 are on the side of the respective flexible blades 33 and 32 so that the fingers 61 and 60 are biased to exert a pushing force upon the blades 33 and 32 respectively to cause their respective contacts 38 and 37 electrically to engage the respective stationary contacts 22 and 21. Under these circumstances, the thermoelectric element 50 is comparatively cool and thus expanded and in its initially tensioned condition. However, if current is caused to flow through the thermoelectric element 50, which is in circuit connection with the contacts 37 and 38 through the abutment 40 and the respective engaging fingers 60 and 61 of the blades then, upon a predetermined current flow through the thermoelectric element 50, said element will become heated, causing it to expand, its expansion permitting the spring 34 to become effective to move the abutment 40 counterclockwise as regards Fig. 1. In response to such counterclockwise movement of the abutment 40, the finger engaged end of the saw tooth notch 56 in said abutment will be moved toward alignment with the flexible contact carrying blade 32 and when said notch and its engaged finger 60 reaches a predetermined position on the lower side of the blade 32 as shown in Fig. 2, the motivating force of the biased finger 60 will be reversed thereby causing it quickly to thrust the blade 32 and its contact 37 toward the stop end 65 of the frame 23 which projects from the portion or side 25 thereof, whereby the circuit formerly passing between the contacts 37 and 21 will be broken. If expansion of the thermoelectric element 50 continues, due to continued or predetermined increase in current flow therethrough, spring 34 will continue to move the abutment 40 counterclockwise as regards Fig. 1, thereby moving the saw tooth notch 55 of the abutment and its engaging end of the finger 61 to the side of the contact carrying flexible blade 33 in which the pushing force of the finger is reversed whereby blade 33 and its contact 38 will be moved away from stationary contact 22 to break the circuit. In moving in this direction, the rigid extension 66 on the blade 33, normally not in engagement with flexible blade 32, will be moved to engage and rest against said blade 32 as shown in the Fig. 3. The Fig. 2 indicates the position of the switch mechanism in which the contact 37 has been moved out of engagement with its stationary contact 21 while

contact 38 is still in circuit completing engagement with its stationary contact 22.

From the aforesaid, it will be seen that in response to a predetermined current flow through the thermoelectric element 50, its expansion is effected, thus permitting the blade spring 34 to become active to actuate the abutment member 40 in a counterclockwise direction as regards Figs. 1, 2 and 3. During the predetermined range of such counterclockwise movement by the abutment 40, finger 60 of the contact carrying flexible blade 32 is adjusted and brought into relative position with the blade 32 so that said finger will thrust the blade and its contact 37 into circuit breaking position as shown in Fig. 2. Continued expansion of the thermoelectric element 50 results in an adjustment of the abutment 40 counterclockwise to bring finger 61 into a position relative to the main body portion of the flexible contact carrying blade 33 so that finger 61 will also thrust its contact carrying blade 33 to move contact 38 out of engagement with contact 22 and the extension 66 of blade 33 into engagement with flexible blade 32 as shown in Fig. 3. Thus, it may be seen that contacts 37 and 38 are successively moved out of engagement with their respective stationary contacts 21 and 22 and their respective circuits broken in response to and in accordance with the expansion of the thermoelectric element 50, due to predetermined current flows therethrough. When the thermo-electric element 50 is permitted to cool due to a reduction or complete discontinuance of current flow therethrough, it will contract and consequently actuate the abutment 40 in opposition to the effort of spring 34 counterclockwise, thus moving said abutment 40 clockwise as regards the Figs. 1, 2 and 3. After the abutment 40 is moved clockwise from its position as shown in Fig. 3, the saw tooth notch 56 and its engaging resilient finger 60 will first be moved to the opposite side of the contact carrying flexible blade 32, thus tending to effect a movement of said blade 32 toward the stationary contact 21. However, in this instance, blade 32 engaged by the rigid extension 66 on blade 33, will be retarded in its movement toward the stationary contact 21 due to the resisting force of the blade 33 which is still being urged into the open position as shown in Fig. 3 by its resilient finger 61. However, as the abutment 40 continues to move clockwise under the effect of the spring 34, being gradually released by the thermo-electric element 50, the notch 55 and its engaging finger 61 will be moved toward alignment with the contact carrying flexible blade 33. As the notch engaging end of finger 61 approaches blade 33 from its position in Fig. 3, finger 61 will gradually exert a weakening force upon blade 33 to urge it into the position as shown in Fig. 3 and when the now opposing forces of fingers 60 and 61 reach a balance at a predetermined position of the abutment 40, moving clockwise, both fingers 60 and 61 will converge and with a snap action thrust their respective contact carrying blades 32 and 33 toward the stationary contacts so that the contacts 37 and 38 on said blades respectively will electrically engage their respective stationary contacts 21 and 22 as shown in Fig. 1. Thus it will be seen that the rigid extension 66 on the contact carrying flexible blade 33 will, when properly adjusted, effect simultaneous engagement of the contacts 37 and 38 with their respective stationary contacts under the effect of the

spring fingers 60 and 61 being slowly adjusted clockwise by the abutment member 49, activated by the spring 34.

It will be seen that the present construction differs from the construction disclosed in the above identified Werner Patent No. 2,242,769 in that the contact carrying flexible blades in this instance are mounted upon the rigid frame and not upon the hinged or movable abutment frame as shown in the patent. The abutment in the present instance mounted upon a blade spring attached to the rigid frame is independently movable relatively to the contact carrying blade springs. These differences in construction provide a switch having the same characteristics as the patented switch but permitting the switch to be made more compact and smaller than would be possible to build the patented switch. The Figs. 1, 2 and 3 illustrate the switch at slightly larger than double size while the Werner patent illustrates a switch of the same characteristics at full size. It may readily be seen that the switch of the present invention, due to its construction, would require considerable lesser material and therefore would be cheaper to produce and at the same time, by requiring less material, provides an important factor under conditions when material supplies for commercial use are being curtailed and restricted.

While the embodiment of the present invention as herein disclosed, constitutes a preferred form, it is to be understood that other forms might be adopted.

What is claimed is as follows:

1. An electric switch comprising in combination, a rigid frame; a movable abutment; flexible means securing the abutment to the rigid frame, said flexible means constantly urging the abutment in one direction; thermo-electric means attached to both the rigid frame and the abutment and operative to actuate the abutment in the opposite direction in opposition to said flexible means; stationary contacts; cooperating flexible contacts secured to the rigid frame; and a flexible biasing element on each flexible contact, said biasing elements respectively seating in contiguous notches in the abutment, each biasing element being operative to actuate its respective flexible contact in one direction or the other, dependent upon the position of the notch occupied by it, relatively to the respective flexible contact.

2. An electric switch comprising in combination, a rigid frame; a movable abutment; a blade spring anchored to the abutment; stationary contacts; cooperating flexible contacts; common means securing the blade spring and flexible contacts to the rigid frame, said blade spring constantly urging the abutment in one direction; thermo-electric means secured between the rigid frame and abutment and being operative to actuate said abutment in the opposite direction in opposition to the blade spring; contiguous notches in the abutment; and a flexible biasing finger on each flexible contact, each finger being seated in a respective notch in the abutment, said fingers being operative to move their respective flexible contacts in one direction or the other in response to movement of their respectively engaged abutment notches to the side of the flexible contact opposite its resultant movement.

3. An electric switch comprising in combination, a rigid frame; a blade spring and two flexible contacts anchored to the rigid frame; an

abutment secured to and carried by said blade spring which constantly urges the abutment in one direction; stationary contacts each adapted to be engaged by a respective flexible contact; a thermo-electric element insulatingly secured to the rigid frame and electrically anchored to the abutment, said element being operative to actuate the abutment in the opposite direction in opposition to the blade spring; and a resilient finger on each flexible contact, one end of each finger being secured to its respective flexible contact, the other end of each finger being seated upon the edge of the abutment and thereby biased, one finger contiguous to the other and in such positions relatively to their respective flexible contacts as to provide over-center mechanism adjusted by the movement of the abutment to thrust said flexible contacts in one direction or the other relatively to the stationary contacts.

4. An electric switch comprising in combination, a rigid frame having an angular extension; two stationary contacts; two longitudinally slotted, resilient contact blades each engageable with a respective stationary contact and anchored at one end to the angular extension of the frame; a blade spring anchored with the resilient contact blades to the frame; an abutment secured to the blade spring which urges the abutment to move in one direction through the slots of the resilient contact blades, transversely thereof, said abutment having two contiguous notches in its outer end edge; a thermo-electric element electrically anchored to the abutment and insulatingly to the frame, said element being operative to operate the abutment in opposition to the blade spring whereby the notches in the actuator are moved across the transverse plane of the resilient blades in one direction or the other; and resilient fingers on each resilient contact blade, biased by seating the free ends thereof in a respective notch of the abutment, said fingers thrusting their respective contact blades in one direction or the other dependent upon to which side of the resilient contact the notches are moved by either the blade spring or thermo-electric element.

5. An electric switch comprising in combination a rigid frame; two stationary contacts; two flexible contacts each adapted to engage a stationary contact, each flexible contact being longitudinally apertured for a portion of its length; a resilient blade; common means anchoring one end of each flexible contact and the blade to the frame, the blade being sandwiched between the flexible contacts; an abutment anchored to the blade which constantly urges the abutment in one direction transversely of the two flexible contacts, said abutment having two contiguous notches in its one end edge; a thermo-electric element electrically secured to the other end of the abutment and insulatingly anchored to the frame, said element being operative to exert an actuating force upon the abutment in opposition to the blade spring whereby the abutment notches are shifted transversely of the respective flexible contacts from one side to the other thereof; a resilient finger on each flexible contact, each finger being biased by seating the free end thereof in a notch of the abutment whereby actuation of the abutment by the thermo-electric element or the blade spring causes said flexible contacts simultaneously to engage or successively to disengage their stationary contacts respectively.

6. A device in accordance with claim 5 in which, however, an adjustable extension is pro-

vided on the one flexible contact, said extension only engaging the other flexible contact when both contacts are disengaged from their respective stationary contacts, whereby concurrent engagement of the flexible and stationary contacts is facilitated in response to actuation of the abutment by the thermo-electric element.

7. An electric switch comprising in combination, a rigid frame; stationary contacts; cooperating flexible contacts one end of each being anchored to the frame; a blade spring secured to the frame; an abutment carried by the blade spring which constantly urges the abutment in one direction transversely of the flexible contacts, said abutment having contiguous notches in its free end edge movable from one side to the other of the transverse plane of a respective flexible contact; thermo-electric means insulatingly secured to the frame and electrically to the abutment, said means being operative to move the abutment in opposition to the blade spring; resilient fingers on each flexible contact, each finger being biased by seating one end in a respective abutment notch, each finger being operative to actuate its respective flexible contact in accordance with the position of the notch it occupies, relatively to its flexible contact; and an adjustable rigid projection on one flexible contact, operative to engage the other flexible contact only when both flexible contacts are disengaged from their respective stationary contacts.

8. An electric switch comprising a base, two insulated, stationary contacts carried by the base; a rigid frame secured to the base; two slotted, flexible blades, one end of each blade being anchored to the frame, the other end of each blade supporting a contact one of which

cooperates with one stationary, the other with the other stationary contact for controlling electric circuits; a blade spring anchored to the frame in superposed relation to the flexible contacts; an abutment carried by the blade spring, said abutment having two contiguous notches in its outer end edge the abutment being movable transversely of the flexible blades through the slots thereof; a resilient finger secured to each of said flexible blades adjacent the respective contacts thereon each finger being biased by placing its free end into pivotal engagement with a respective notch in the abutment, the bias of each finger effecting operation of the contact carrying blades toward or away from their respective cooperative stationary contacts in accordance with the position of the notches in the abutment relatively to the respective contact carrying blades; and a thermo-electric element insulatingly connected to the rigid frame and electrically to the abutment, said element being operative in accordance with current flow therethrough either to actuate said abutment against the effect of its supporting blade spring to cause 25 contact disengagement or to permit said blade to move the abutment to effect contact engagement.
